(Cl. D87—3)

To all whom it may concern:

Be it known that I, Richard S. Temko, a citizen of the United States of America, residing in the Borough of Manhattan, city of New York, county of New York, and State of New York, have invented a new, original, and ornamental Design for a Plastic Unit for use on Handbags or the like, of which the following is a specification, reference being had to the accompanying drawing, forming part thereof.

Figure 1 is a top view in perspective of a plastic unit for use on handbags or the like, showing my new design.

Figure 2 is a bottom view in perspective of the unit, shown in Figure 1.

I claim:

The ornamental design for a plastic unit for use on handbags or the like, as shown.

RICHARD S. TEMKO.
